UNITED STATES PATENT OFFICE.

WILLIAM W. ROBERTSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

NEEDLE MOTION FOR AXMINSTER LOOMS.

Application filed June 13, 1927. Serial No. 198,393.

This invention relates to needle motions for Axminster looms and it is the principal object of the invention to provide means for increasing the dwell of the needle when in the shed to allow more time for the operation of the selvage shuttle.

In the usual Axminster loom there is employed a long needle inserted from one side of the loom through the open shed, said 10 needle carrying the filling and having an eye in the advancing end thereof. A small shuttle on that side of the cloth opposite the side from which the needle enters the shed is made to traverse the path of the eye of 15 the needle when the latter has passed entirely through the shed so as to interlace the selvage thread with the filling.

In recent attempts to increase the speed of wide Axminster looms it has been found 20 that the needle because of its weight and length vibrates sufficiently to interfere with the perfect operation of the selvage shuttle. It is an important object of my present invention to provide a needle motion for a 25 loom running at an increased speed but wherein the needle or the eye of the needle is given a slight dwell to permit the passage of the selvage shuttle so that the operation of the latter may be more certain.

30 It is also found that the increase in the speed of an Axminster loom results in straining the parts which actuate the needle and it is another object of my invention to provide a means for absorbing the shock incident to the motion of a needle to the end that the latter may get into motion more gradually than would otherwise be the case without my present invention.

It is a more specific object of my invention 40 to provide an improved drive for the cable or rope of an Axminster needle motion wherein a collapsible connector is interposed between the constantly driving part and the parts associated with the drum, said collapsible part permitting a continued movement on the part of the driving mechanism while the needle is at rest to permit the proper operation of the selvage shuttle.

With these and other objects in view which 50 will appear as the description proceeds, my invention resides in the combination and arrangement of parts hereinafter described and set forth in the claims.

In the accompanying drawings, wherein I

have shown a convenient embodiment of my 55 invention,

Fig. 1 is a side elevation of the right hand end of an Axminster loom shuttle motion showing the needle motion with my improvements applied thereto, 60

Fig. 2 is a vertical section on line 2—2 of Fig. 1,

Fig. 3 is a fragmentary horizontal section on line 3—3 of Fig. 1,

Fig. 4 is a top plan view of the selvage 65 shuttle and operating parts taken in the direction of arrow 4, Fig. 1,

Fig. 5 is a detailed view on an enlarged scale showing the collapsible portion of the connection between the regularly moving 70 driving part and the actuating segment, parts being in section, and

Fig. 6 is a view of the portion of mechanism shown in Fig. 1 but with the parts in a different position. 75

Referring to the drawings it will be seen that I have provided an end frame 10 which may project from the right hand end of the loom and have journaled therein a constantly rotating shaft 11 carrying a crank 80 arm 12. Said shaft 11 may be driven in any approved manner forming no part of my invention and may have either a uniform or a variable movement. A segment 13 is pivoted at 14 to the frame and has teeth 85 15 which mesh with the pinion 16 moving with a drum 17. Said drum actuates a cable or rope 18 which moves around fixed guide sheave 19 and movable guide sheave 20.

In order to take up slack in cable 18 I 90 provide a lever 21 having one end weighted as at 22 and the other end provided with a bearing 23 for the movable guide sheave 20. A hold pawl 24 is pivoted to the frame 10 at 25 and cooperates with a segmental ratchet 95 26 to hold said lever 21 in any of its adjusted positions. The lever 21 will move the sheave 20 to the right when sufficient slack in the rope 18 permits of such movement and the pawl 24 will engage the teeth of 100 the ratchet 26 to prevent retrograde movement.

A needle block 27 is secured to the cable and slides on a guide 28 to direct movement of the needle 29 as the latter reciprocates in a horizontal line into and out of the warp shed. As the crank arm 12 moves in the direction of arrow A the segment, pinion

and drum will act to move the needle back and forth so that the weft W may be inserted in the fabric.

On that side of the cloth opposite the 6 needle motion is the usual selvage shuttle motion comprising a stand 30 through which extends an upright oscillating shaft 31 to which is secured an actuator arm 32. The selvage shuttle 33 moves in an arcuate guide 10 slot 34 formed in a stand 35 and a mouth 36 is provided for receiving the eye end of the needle 29. The latter may be positioned against upward movement by a guard 37 moving with the arm 32 and a pad or block 15 38 held on the stand 30 may position the needle to prevent the same from being too low. I do not consider the guard and block necessary but they have been found in practice to assist in the placing of the needle 20 when wide Axminster looms operate at high speed.

An arm 39 fast with the upright oscillating shaft 31 is attached to a connector 40 which receives reciprocating movements 25 from mechanism not shown, the reciprocation of said rod 40 requiring the shuttle 33 to move back and forth in the arcuate slot 34 so that the nose of the shuttle will pass through a reduced part 41 of the needle 29 30 and through the loop in the filling. The thread S which extends from the selvage to the shuttle in this way holds the weft W as the needle returns to the right hand side of the loom. The matter thus far described 35 is of common construction and forms no part of my present invention and may be constructed and operated as well understood by those skilled in the art. The slack taking-up device of which lever 21 is a part is not necessarily employed and my invention is not confined to the use of any particular form 40 of shuttle motion for the selvage thread.

As previously stated my invention has as an important object the provision of means 45 for causing a dwell in the eye of the needle to allow more time for the passage of the selvage shuttle. The particular means for accomplishing this result as shown herein includes an improved form of connector between the arm 12 on the driving shaft 11 and the segment 13. Accordingly, I pivot the connector 50 to the crank arm 12 and provide said connector with a cross head 52 having portions extending on either side of 50 the central line of the connector. In each 55 end of the cross head I secure bolts 53 which extend through a bearing member 54 having pivotal connection with a stud 55 fast on the segment 13. Heavy compression 60 springs 56 surround the bolts 53 and lie between the cross head 52 and the bearing 54. A tongue 57 projects from the cross head and has an end adapted for engagement with a part of the bearing 54.

65 An abutment 60 having a block 61 is se-

cured to the frame 10 and may have a shock absorbing face formed of leather or other suitable material as at 62 to be engaged by the segment 13 to effectively limit movement of the rack or segment to the left.

At the beginning of a needle inserting movement the parts will be in the full line position shown in Fig. 6 with the crank arm moving in the direction of arrow A. As the arm 12 moves upwardly the connector 50 will start to move inwardly gradually and the springs 56 will transmit the thrust of the connector 50 to the bearing 54 and the latter in turn will tend to move the segment 13 about the pivot 14. If the drum and other parts of the needle moving mechanism are slow in getting into motion due to their weight the springs 56 will compress slightly as the arm 12 continues to move about its center and if the parts have not gotten into motion by the time the tongue 57 engages the bearing 54 these two parts will establish direct connection between the arm 12 and the segment 13 so as to cause the needle moving parts to move at the correct speed.

After the parts have been set in motion and the segment has moved to the left from the position shown in Fig. 6 the end of the rack or toothed part 15 will engage the abutment 60 when the crank arm 12 and the connector 50 are in some such a position as that indicated in light dotted lines in Fig. 1. The segment is brought to rest when the needle is properly positioned and the selvage shuttle 33 may therefore begin its movement along the slot 34 to lay the selvage thread through the loop of the filling W. The needle will continue to remain at rest while the arm 12 moves from the position in light dotted lines to that shown in full lines and will remain at rest until the arm and connector reach the position shown in heavy dotted lines in Fig. 1. During this movement the springs 56 are compressed, said springs providing means whereby the crank arm 12 can continue to move while the needle remains at rest.

By referring to Fig. 1 it will be seen that the needle will be at rest while the crank arm is passing through a comparatively large part of its angular movement around shaft 11. The length of time permissible for the flight of the shuttle 33 is of course determined by the length of dwell of the needle or needle eye. I find with the use of the device set forth herein that the shuttle can move at a comparatively slow rate of speed so that when the looms to which the invention are applied are speeded up to run at a considerably faster rate the shuttle motions can move practically at their original speed so as to insure proper movement thereof without the danger of mis-threading or breaking either the filling or selvage warp.

From the foregoing it will be seen that I have provided means for producing a dwell in the motion of the needle eye, this result being accomplished by a form of connection 5 between the driving shaft of the needle motion and the segment, the connection yielding to cause or permit a dwell in the movement of the needle. This connection also tends to absorb the shock which usually results when the needle motion is required to operate at an increased rate.

Having thus described my invention it will be apparent that changes and modifications may be made therein by those skilled 15 in the art without departing from the spirit and scope of the invention and I do not wish to be limited to the details herein disclosed, but what I claim is:

1. In a needle motion for Axminster looms 20 having a selvage shuttle, a constantly moving driving mechanism, operating mechanism for the needle, a stop for said operating mechanism, and a motion absorbing connection between the driving mechanism and 25 the operating mechanism, said operating mechanism being brought into engagement with the stop during a portion of the movement of the constantly moving driving mechanism, said connection absorbing motion 30 from the driving mechanism as the latter continues to move and the needle operating mechanism remains substantially at rest.

2. In a needle motion for Axminster looms 35 having a selvage shuttle, a regularly moving driving mechanism, operating mechanism for the needle, a fixed stop to be engaged by a part of the operating mechanism, and a yielding connection between the driving mechanism and the operating mechanism to 40 move said operating mechanism against the stop as the driving mechanism moves and to yield as the driving mechanism continues to move while the operating mechanism is arrested by the stop.

3. In a needle motion for Axminster looms 45 having a selvage shuttle, a regularly moving member, operating mechanism for the needle including an oscillating segment, a stop for the segment, and a yielding connector between the regularly moving member and the segment to yield under normal 50 operating conditions as the regularly moving member continues to move while the segment is in contact with the stop to produce a dwell in the motion of the needle.

4. In a needle motion for Axminster looms 55 having a selvage shuttle, a driving member having a regular movement in a rotary path, operating mechanism for the needle including a segment to oscillate, a stop for the segment, a connector between the driving member and the segment, and yielding means forming part of the connector and interposed between the segment and the 60 member to yield during the regular move-

ment of the needle motion while the member continues to move in its rotary path when the stop is in engagement with the segment.

5. In a needle motion for Axminster looms 70 having a selvage shuttle, regularly moving driving mechanism, operating mechanism for the needle, a yielding connection between the driving and operating mechanisms, and fixed means to cause a periodic yielding of 75 said connection during the normal operation of the loom to cause a dwell in the movement of the needle and the operating mechanism therefor as the driving mechanism continues to move.

6. In a needle motion for Axminster looms 80 having a selvage shuttle, a regularly moving driving mechanism, operating mechanism to move the needle, and yielding means to transmit the movement of the driving mechanism to the operating mechanism, said yielding means being compressed during the 85 normal operation of the loom to cause a dwell in the movement of the needle and the operating mechanism therefor as the driving 90 mechanism continues to move.

7. In an Axminster loom having a selvage 95 shuttle, a weft laying needle, a regularly moving driving mechanism, operating connections operatively connecting the needle and the driving mechanism at all times, said connections including a yielding element and means to arrest movement of the needle during the normal operation of the loom and cause yielding of the connections as the driving 100 mechanism continues to move.

8. In an Axminster loom having a selvage 105 shuttle, a weft laying needle, a regularly moving driving mechanism, operating mechanism for the needle, a yielding connection to communicate driving power to the needle operating mechanism and interposed between the operating and driving mechanisms, and means to limit movement of the needle on its weft laying stroke during the normal 110 operation of the loom, said means causing a yielding of the connections as the driving mechanism continues to move.

9. In an Axminster loom having a selvage 115 shuttle, a weft laying needle having an eye on one end through which the weft extends, regularly moving driving mechanism, operating connections including a yielding member to communicate driving power to the needle operating mechanism, and means to cause a regular yielding of said member during the normal operation of the loom to hold the eye of the needle and the operating connections therefor fixed with respect to the selvage shuttle while the driving mechanism 120 continues to move.

10. In a needle motion for Axminster 125 looms having a selvage shuttle, a regularly moving driving shaft having a needle inserting movement, operating mechanism for 130

- the needle including a fixed pinion and a segment meshing therewith, a yieldable connection between the shaft and the operating mechanism for the needle, and means to arrest movement of the needle and the operating mechanism therefor prior to completion of the needle inserting movement of the shaft and during the last part of the needle inserting movement of the shaft.
11. In a needle motion for Axminster looms having a selvage shuttle, a constantly moving driver for said needle, operating connections for the needle, motion absorbing means including two relatively movable co-acting elements interposed between the driver and the operating connections, and means to hold one of the elements of the motion absorbing means stationary during a portion of the movement of the driver, whereby a part only of the movement of the driver is communicated to the needle.
12. In a needle motion for Axminster looms, a needle to be reciprocated, an oscillatable segment operatively connected to the needle, a regularly moving driving member, a connector interposed between the driver and segment to communicate motion from the driving member to the segment, and yieldable means forming part of the connector to absorb motion of the driver when the motion of the segment is arrested.
13. In a needle motion for Axminster looms, a needle to be reciprocated, an oscillatable segment operatively connected to the needle, a regularly moving driving member, a connector interposed between the driver and segment to communicate motion from the driving member to the segment, yieldable means forming part of the connector to absorb motion of the driver when the motion of the segment is arrested, and a stop to engage the segment to arrest motion thereof.
14. In a needle motion for Axminster looms, a needle to be reciprocated, an oscillatable segment operatively connected to the needle, a regularly moving driving member, a connector interposed between the driver and segment to communicate motion from the driving member to the segment, and yieldable means forming part of the connector to absorb motion of the driver when the motion of the segment is arrested, said connector having provision for limiting relative movement of the segment and the driving member in the direction in which the yielding means permits relative movement of the driver and segment.
15. In a needle motion for Axminster looms, a needle to be reciprocated, an oscillatable segment operatively connected to the needle, a regularly moving driving member, a connector interposed between the driver and segment to communicate motion from the driving member to the segment, and yieldable means forming part of the connector to absorb motion of the driver when the motion of the segment is arrested, said connector having a tongue to be operatively related to the segment to limit movement of the segment toward the driver.
16. In a needle motion for Axminster looms, an oscillatable segment, a regularly moving driver, a connector interposed operatively between the driver and the segment, a bearing carried by the segment and having sliding contact with a portion of the connector, and yielding means interposed between the connector and the bearing.
17. In a needle motion for Axminster looms, an oscillatable segment, a regularly moving driver, a connector interposed operatively between the driver and the segment, a bearing carried by the segment and having sliding contact with a portion of the connector, yielding means interposed between the connector and the bearing, and a tongue carried by the connector to engage the bearing to limit movement of the segment toward the driver.
18. In a needle motion for Axminster looms, an oscillatable segment, a regularly moving driver, a connector interposed operatively between the driver and the segment, a bearing carried by the segment and having sliding contact with a portion of the connector, yielding means interposed between the connector and the bearing, and means between the bearing and connector to limit relative movement of said bearing and connector when the yielding means permits relative movement of the segment and the driver.
19. In a needle motion for an Axminster loom, a driving member movable through a given interval of time, a needle, a movable segment and fixed pinion device operatively connected to the needle, said needle and device being movable through a correspondingly shorter interval of time, and motion absorbing mechanism interposed operatively between the device and the member to absorb motion from the member while the latter moves after the expiration of the time interval of the needle and device.

In testimony whereof I have hereunto affixed my signature.

WILLIAM W. ROBERTSON.
